UNITED STATES PATENT OFFICE.

JAMES A. BAUGHMAN, OF CHARLOTTE, MICHIGAN, ASSIGNOR OF ONE-HALF
TO JAMES L. WHITFORD, OF SAME PLACE.

TOE-WEIGHT.

SPECIFICATION forming part of Letters Patent No. 407,768, dated July 30, 1889.

Application filed December 31, 1888. Serial No. 295,004. (No model.)

To all whom it may concern:

Be it known that I, JAMES A. BAUGHMAN, a citizen of the United States, residing at Charlotte, in the county of Eaton and State of Michigan, have invented new and useful Improvements in Toe-Weights, of which the following is a specification.

The invention relates to improvements in toe-weights for attachment to the shoes of trotting-horses; and it consists in a certain novel construction and combination of parts fully described hereinafter in connection with the accompanying drawings, and specifically pointed out in the claim.

15 In the drawings, Figure 1 is a perspective view of a horseshoe with the improved toe-weight applied in the operative position thereto. Fig. 2 is a transverse horizontal sectional view of the weight and the spur. 20 Fig. 3 is a detail view of one of the sections of the weight.

Referring by letter to the drawings, A designates the horseshoe, of any ordinary shape or kind, which is provided at its front with 25 the upwardly and rearwardly inclined spur B, which is dovetailed in cross-section or tapered toward its rear side. This spur is welded to the shoe, but may be made of the same piece.

C designates the weight, which comprises 30 the sections or halves D D, formed by dividing the weight centrally, and the said sections or halves are provided in their adjacent rear corners or edges with the angular grooves E E, which, when the sections or halves are put 35 together, communicate and form a dovetailed channel which fits the spur.

The sections or halves are provided on their front sides with the forwardly-projecting ears F F, which are in contact, and are provided 40 with registering-apertures G G, engaged by the adjusting-bolt H, as clearly shown in Figs. 1 and 2. The rear side of the weight is concavely rounded, as shown in Fig. 2, to fit the hoof of the horse.

The advantage of the improved weight, 45 constructed in sections or halves which are bolted together and bear against opposite sides of the spur is that it may be applied at any time or replaced by a weight of a different size, adapted to bear against the hoof of 50 the horse.

It will be observed that the spur B is of greater length than the weight, in order that the latter may be more readily adjusted lengthwise on the spur, to throw the weight 55 away from or nearer to the shoe or bottom of the hoof. This adjustment is provided to accommodate various shaped hoofs and of horses having different movements. The dovetailed foundation of the spur and weight 60 avoids a loose attachment by wear, and rattling of the weight is avoided.

A further advantage of the improved weight is that, being formed in sections, the channel 65 is more easily cut.

Having thus described the invention, I claim—

A horseshoe having an integral elongated dovetailed spur on the upper side of the toe thereof, in combination with a toe-weight constructed of two equal sections, the rear of each of which is concaved and has the half of a dovetailed recess to engage the spur, and the front provided with apertured lugs, and a clamping-bolt adapted to pass through the 75 apertured lugs and adjustably secure the weight on the spur close to the hoof, substantially as described.

In testimony that I claim the foregoing as my own I have hereto affixed my signature in 80 presence of two witnesses.

JAMES A. BAUGHMAN.
